UNITED STATES PATENT OFFICE.

ARON PETERSON, OF CHICAGO, ILLINOIS.

WIRE MATTRESS FABRIC.

1,207,998.

Specification of Letters Patent.

Patented Dec. 12, 1916.

Application filed March 1, 1916. Serial No. 81,379.

To all whom it may concern:

Be it known that I, ARON PETERSON, a citizen of the United States, residing at Chicago, in the county of Cook and State of Illinois, have invented certain new and useful Improvements in Wire Mattress Fabrics, of which the following is a specification:

My invention relates to bed bottom spring supports and its object is to overcome a difficulty and an objection that is common to fabrics of this kind, namely, that when not stretched or held spread the links bind, or become wedged, or tangled out of their normal relations.

15 The present invention provides a construction, combination of parts, or form of individual links, which permits the use of the structure as a whole as if it were cloth instead of wire links; so that when thrown into 20 a heap it will not become a knotted or tangled mass. The present improvement is therefore adapted to be used as canvas or netting which may be rolled, or folded up quickly in substantially the same way and 25 be unrolled or straightened out by reason of the freedom of the links to fall into their proper relative positions under the force of gravity alone.

I am aware that there are constructions 30 which resist tangling up and which permit the structure, or wire fabric, to be rolled up on an axis parallel to the pivotal axes of the links, but the present invention attains the non-tangling result in a structure that, as a 35 whole, is flexible from corner to corner as well as from side to side, and in a structure which does not sacrifice the greatest possible strength in the interest of the non-tangling object, or add elements for that purpose, or 40 increase the cost of construction, or make more difficult the process of construction.

With these general objects in view, the invention hereinafter described consists of the novel form of link, and in its combination 45 with connected links described herein in detail, illustrated in the accompanying drawing, and more particularly defined in the appended claims.

In the drawing—Figure 1 is a plan view of 50 what may be termed a section or piece of wire fabric embodying my invention. Fig. 2 is a vertical section through several of the links. Fig. 3 illustrates the flexibility or relative 55 movability of several connected links in directions other than those which are controlled

by the pivotal movements of the links. Fig. 4 is a perspective view of one of the individual links.

As shown most clearly in Fig. 4, each link is a single piece of wire with its ends 2 and 3 side by side, and forming three projections or arms one of which consists of what may for convenience be called the initial leg 4 leaving the end and loop 2 and of the final leg or run 5 which terminates in the end and loop 3. The other two projections are, substantially, endless loops 6 and 7 which are free or open their entire lengths from tip to point of junction 8 with the other projections. Starting at the loop or eye 2 the link 70 is formed by making a right angle bend 9, then a return bend 10, another similar return bend 11, a right-angle bend 12 engaging the bend 9, and, finally, a return bend 13 which embraces a substantially straight 75 or uninterrupted run 14 of loops 6 and 7, and ends in the leg or run 5 and its loop or eye 3.

As shown in Figs. 1 to 3, the eyes, loops, or pivot portions 2 and 3 are engaged with the run 14 on opposite sides of the return 80 bend 13, which serves not only to bind the projection or legs 4 and 5 to the projections or legs 6 and 7, but also to prevent the ends 2 and 3 or the legs 4 and 5 from moving along the run 14 or longitudinally of the 85 loops 6 and 7.

Fig. 3 shows six of the individual links or units of Fig. 4 and in said Fig. 3 the six links are designated separately by the numerals 15, 16, 17, 18, 19, and 20. Notwithstanding the restriction to substantially pivotal movement only of the engagements of loops or eyes 2 and 3 with the leg 14, the links, as shown, are given so much latitude 90 in the way of relative angular movement 95 and positions that the junctions 8 of connected links may be brought together as in the case of links 17 and 20 by reason of the fact that each loop 6 and 7 is open or unobstructed all the way to said junction. When so brought together the interengaging loops 6 and 7 cannot bind or stick upon each other so as to prevent their resumption of normal positions shown in Fig. 1 when one side or edge of the structure or fabric is grasped in 100 the user's hands and straightened out. In other words the fabric may be shaken out or straightened from a crumpled up mass in the same manner as a blanket or piece of cloth after it has been thrown into a heap. 110

The extended relative movements of loops 6 and 7 of adjacent connected links will, as also indicated by the relations of the links in Fig. 3, make it possible to roll up the structure of Fig. 1 from corner to corner diagonally as well as from either side, but the diagonal roll would be a little larger. Such a handling of many of the heretofore provided structures would so badly bind and entangle links and joints that only considerable expert labor could untangle or release them.

It will be noticed that there are no separate clips, bands or loop attachments to make joints or hold the same in proper relation. The bend 13, which also serves as a lateral stop for the pivot eyes 2 and 3, is a smooth and firm support for the run 14 of loops 6 and 7 against the strains imposed through arms 4 and 5, and as the eyes 2 and 3 of the latter are immediately adjacent to the loop or bend 13 there is no effective bending strain upon the run 14 even with the load strain being wholly along the lines of the arms 4 and 5, which would not be possible in practice where the strain is just as great longitudinally of the loops 6 and 7. The bend 13 being, exclusive of the eyes 2 and 3 which may be made either first or last, the final bend, there is no obstacle in the way of a prior bend or formation in the way of any subsequent bend or formation in the link, which makes the structure of the link or unit exceedingly simple as well as strong, there being no part which is capable of opening aside from the eyes 2 and 3, and

these may be entirely closed by welding or soldering if desired.

Having thus described my invention, I claim as new and desire to secure by Letters Patent—

1. A link for a wire fabric, which consists of a single wire bent a certain distance from its initial end at right angles, then bent upon itself to form an elongated loop extending to the right-angle bend first-mentioned and beyond said bend to form another similar loop on the other side of the bend, and finally bent around said first-mentioned right-angle bend and the elongated loops and returning to its starting point, said starting point being the two ends of the wire, which ends are formed into eyes or loops adapted to engage the elongated loops of an adjoining link on opposite sides of the bend around the right-angle bend. 45

2. A wire fabric consisting of links each of which has three arms or projections, two of which form substantially one long loop and the third extends from the middle of said long loop at right angles thereto and consists of a right angle bend in said wire and a loop around the long loop, said third arm being the terminal runs of the wire lying side by side, or parallel to each other, and terminating in pivot eyes adapted to be connected with the long loop of an adjacent link. 60

In testimony whereof I have hereunto subscribed my name.

ARON PETERSON.
